UNITED STATES PATENT OFFICE.

SAMUEL C. MAY OF MODESTO, CALIFORNIA.

PIER-PROTECTOR.

1,092,731.

Specification of Letters Patent.

Patented Apr. 7, 1914.

Application filed September 5, 1913. Serial No. 788,241.

To all whom it may concern:

Be it known that I, SAMUEL C. MAY, a citizen of the United States, and a resident of Modesto, in the county of Stanislaus and State of California, have invented a new and Improved Pier-Protector, of which the following is a full, clear, and exact description.

This invention relates to means for protecting bridges, piers or the like from damage due to floating logs, ice or debris carried by currents of water.

Among the objects, therefore, of this invention is to provide a means of a simple, reliable and permanent nature adapted to be secured to, or arranged in association with a pier or the like projecting into or upwardly from a body of water, said device being so arranged with respect to the pier as to float upon the surface of the water whereby it will always be automatically maintained at proper elevation with respect to said surface.

The foregoing and other objects of the invention will hereinafter be more fully described and claimed and illustrated in the drawings forming a part of this specification in which like characters of reference indicate corresponding parts in both the views, and in which—

Figure 1 is a vertical section on the line 1—1 of Fig. 2, showing a pier in side elevation; and Fig. 2 is a transverse section on the line 2—2 of Fig. 1, and Fig. 3 is a perspective view of a pier provided with my improvement.

A device made in accordance with this invention may be of any suitable strong and durable material and is adapted to be fitted to any size or form of pier or the like to be protected thereby.

As shown, the device comprises a pontoon-like structure indicated at 10 and comprising a preferably hollow body embracing the upstream side or edge of the pier 11. The form of the pontoon or guard, as it will be hereinafter termed, corresponds to the general form of the cross section of the pier or device to which it is to be applied. 50 The exact internal construction of the guard

is immaterial so long as it constitutes a device which will automatically be buoyed up to a certain elevation with respect to the surface of the water and will be of a strong and permanent nature. The rear or downstream end of the guard is preferably open, except as noted below, whereby it may be easily applied to the pier, protecting the front or upstream face or edge thereof as well as the sides.

At 12 I show one or more straps, preferably of metal, which are adapted to be connected at their ends at 13 to the rear corners of the guard. Said connections may be in the form of hinges 13' or of such nature as to admit the pier within the guard and then secure the same so as to prevent displacement of the guard from its embracing position around the pier, due either to the elements or the pranks of mischievous or malicious persons.

Cushioning devices shown as in the nature of coil springs 14 are connected to the inner surface of the guard at a number of places whereby the impact of the guard upon the pier is relieved and damage to the pier is prevented by the hammering or battering action of logs or other drift material in the current of water. Each of said springs is, preferably connected permanently at one end as shown at 15 to the inner wall of the guard, and the other end is connected preferably to a head 16 which may be in the nature of a shoe or block adapted to slide up and down the outer surface of the pier as the guard rises or falls with the surface of the water.

Having thus described my invention, I claim as new and desire to secure by Letters Patent—

1. In a pier protector, the combination of a floating guard, cushioning devices connected to the inner vertical wall thereof adapted to bear against the pier, and means applied to the rear end of the guard to prevent separation thereof from the pier.

2. In a pier protector, the combination of a hollow buoyant guard adapted to conform to the upstream and lateral portions of the pier, a plurality of cushioning springs con-

nected at one end to the guard, a shoe for the other end of each spring adapted to glide along the face of the pier, and a strap extending across from one corner of the rear 5 end of the guard to the other and adapted to loosely embrace the rear face of the pier, substantially as set forth.

In testimony whereof I have signed my name to this specification in the presence of two subscribing witnesses.

SAMUEL C. MAY.
